INCLINABLE FOUR-SIDE METAL FORMING MACHINE

Burton F. Lewis, Trumbull, Conn., assignor to The U. S. Baird Corporation, a corporation of Connecticut
Filed July 8, 1960, Ser. No. 41,618
14 Claims. (Cl. 29—34)

This invention relates to a metal forming machine, specifically of the type known as a four slide machine in which there is a bed or frame provided with means forming a work station and multiple slides carrying tools for performing various operations on work at said station, such, for example, as wire or ribbon metal.

It is an object to provide a machine of this type which provides more versatile equipment for this type of work than machines hitherto generally available.

Machines of this type have generally been of the form operable in a horizontal position, although vertical machines have also been developed, but it has been found that strictly horizontal or vertical machines are limited to a smaller range of jobs as compared to a machine that can be operated in both planes. Also the forming area of most of these machines is somewhat limited and congested for certain types of work. It is therefore also an object to provide a machine which has the advantages of a machine which can be operated in both horizontal and vertical positions as well as any position between the horizontal and vertical positions, as may best suit the particular article to be produced.

A further object is to provide a machine having a greater, less limited and less congested forming area.

Another object is to provide a machine having a bed or frame providing more space for mounting of press units between the feeding mechanism for the wire or ribbon stock and the forming position, thus expanding the ability to do a larger amount of press work. For this purpose the press units are designed so they may be assembled and applied as such to the machine and may be operated from either the normal front or back shaft as determined by the machine where operated in the horizontal position, and the ability to operate these presses from either of these two positions offers further advantage when the machine is shifted to the vertical position, in that the press can be so located that the scrap will fall by gravity and present less problems in ejecting.

It is a particular object to provide a new and improved type of form bracket which not only is of itself a great improvement over the old form of fixed bracket, but may be mounted in different positions on the bed or frame of the machine with respect to the forming area, specifically at either the back or one side thereof, thus greatly increasing the possible variations in mounting and locating the tool elements, and also making it possible to operate the press units close up to the forming area.

It is a further important object to provide an improved construction of form bracket which includes a wide flat vertical mounting surface on the front side of the bracket on which a great variety of holder blocks may be mounted in various positions to best suit the particular type of tooling situation to be used.

It is also an object to produce a construction of form bracket which provides a more open area for the front, rear and side slides.

Still another object is to provide a construction whereby a form at the work station may be mounted and supported from the under side of the bed by a bracket devised for this purpose, and may also provide for a motion to be used for either stripping or doing a certain

2

amount of forming work which may be operated from the under side of the bed.

With the foregoing and other objects in view, I have devised the construction illustrated in the accompanying drawings forming a part of this specification. It is, however, to be understood the invention is not limited to the specific details of construction and arrangement shown, but may embody various changes and modifications within the scope of the invention.

In these drawings:

FIG. 1 is an end view of the machine showing it for operation in the horizontal position;

FIG. 2 is a front view thereof with parts broken away to more clearly show the construction;

FIG. 3 is an end view showing the bed or frame in the vertical position, and also indicating in broken lines an intermediate inclined position;

FIG. 4 is a top plan view of a portion of the supporting base and parts of the elements for mounting the bed or frame on this base;

FIG. 5 is a partial side elevation and a partial section of the mechanism of FIG. 4, the section being substantially on the plane of line 5—5 of FIG. 4;

FIG. 6 is a partial end view of the device of FIGS. 4 and 5 looking from the right of these figures;

FIG. 7 is a plan view of one of the elements for mounting the bed or frame on the base;

FIG. 8 is a side view thereof;

FIG. 9 is a plan view of another element for mounting the bed or frame;

FIG. 10 is a top plan view of the machine when in a horizontal position, showing the improved form bracket mounted in the so-called back mounting position, and showing a single press unit associated with this bracket and mounted for operation from the front shaft;

FIG. 11 is also a plan view of a portion of the machine with the feeding and other elements shown in dotted lines, but showing the improved form bracket in its so-called side mounted position, and showing how this will permit the use of a pair of press units operating between the feed mechanism and the work station;

FIG. 12 is a similar plan view of a portion of the machine at the work station using a similar side mounting for the form bracket, and showing how the two press units associated therewith may be operated one from the front shaft and one from the back shaft;

FIG. 13 is a plan view showing how the plurality of horizontal slides, specifically four in number, may be arranged at the work station to carry tools for operation on a work piece at this station, and their relation to the form bracket; it also indicates how the form bracket, portions of which are broken away, may be mounted in the back mounted or side mounted positions;

FIG. 14 is a vertical section of a portion thereof taken substantially on line 14—14 of FIG. 13;

FIG. 15 is a top plan view of a portion of the work station showing two of the slides associated therewith but with two of them omitted, and showing how other work-forming elements may be mounted from the under side of the bed or frame and also operated from this under side of the bed or frame;

FIG. 16 is a section thereof substantially on line 16—16 of FIG. 15;

FIG. 17 is a plan view of a portion of the bed or frame showing the improved form bracket in the side-mounted position, and with the auxiliary form bracket mounted thereon;

FIG. 18 is a partial side view and partial section looking from the right of FIG. 17 with parts of the main form bracket broken away;

FIG. 19 is a front elevational view of the main form

bracket showing how various tool elements may be mounted thereon;

FIG. 20 is a side elevation looking toward one end of this form bracket, or that is, from the right of FIG. 19, and showing a portion of the bed or frame in section;

FIG. 21 is a top plan view of the elements shown in FIGS. 19 and 20;

FIG. 22 is a plan view of a portion of the elements shown in FIGS. 19 to 21, but showing how certain of them may be mounted in a different position;

FIG. 23 is a front detail of the improved form of bracket;

FIG. 24 is an end view thereof looking from the right of FIG. 23;

FIG. 25 is a top plan view thereof;

FIG. 26 is a side elevation of the auxiliary form bracket;

FIG. 27 is a front elevation thereof looking from the left of FIG. 26;

FIG. 28 is a bottom plan view looking toward the bottom of FIG. 26;

FIG. 29 is a partial end elevation of the main form bracket and showing the auxiliary bracket mounted thereon;

FIG. 30 is a plan view of the press attachment assembled as a unit;

FIG. 31 is an end view thereof looking from the left of FIG. 30;

FIG. 32 is a transverse vertical section substantially on line 32—32 of FIG. 30;

FIG. 33 is a partial side elevation and partial longitudinal section of the press attachment or unit;

FIG. 34 is an end elevation of the feed mechanism;

FIG. 35 is a side elevation thereof;

FIG. 36 is an end elevation looking from the left of FIG. 35;

FIG. 37 is a top plan view of the work clamp;

FIG. 38 is a side elevation thereof with a portion of the frame broken away;

FIG. 39 is a plan view of the cut-off mechanism;

FIG. 40 is a side elevation thereof with a portion of the bed or frame shown in section; and

FIG. 41 is a side view of a portion of the cut-off mechanism arranged for cutting flat ribbon stock and with a portion of the frame shown in section.

Mounting for the Bed or Frame

Referring to the drawings, the machine is shown as comprising a bed or frame 1 mounted on a supporting base 2. This supporting base comprises a substantially flat rectangular plate 3 forming a foot member, and a pair of laterally spaced upright supporting legs 4 and 5 secured to the top of the member 3 by any suitable means, such, for example, as welding their lower ends thereto. The legs are of oblong, hollow construction with flat side walls 6 and curved front and rear edge walls 7 connecting the side walls.

The bed 1 of the machine is in the form of a substantially flat rectangular frame on which is mounted the various devices or elements for performing the various operations on the work, such, for example, as wire or flat ribbon stock which also may be called a flat wire in a broad sense. The bed or frame is mounted on the upright legs 4 and 5 of the base 2 so that the machine may be operated either in the horizontal position, as shown in FIGS. 1 and 2, a vertical position as shown in full lines in FIG. 3, or in any intermediate inclined position, one of which is shown in broken lines in FIG. 3. For this purpose the bed is mounted on a supporting bar 8 supported at its opposite ends in the legs 4 and 5 of the base 2, and the bed is supported on this bar by means of mounting plates 9 and 10. Welded to one end of the plate 9 is a lug 11 embracing the bar 8, and the bed or frame 1 is bolted to the top of this plate through the openings 12, a similar lug 13 being welded to the other

end and pivotally connected to a lug 14 welded to one side of the leg 4. The other end of the bed is bolted through the openings 15 to the plate 10, to the under side of which is welded a lug 16 embracing the bar 8, and at its other end is welded a similar lug or ear 17 pivotally connected at 18 to the lug or ear 14 welded to the side of the leg 5, the pivot 18 being in a line with the pivot for the plate 9.

The supporting bar 8 is supported at its opposite ends for pivotal or turning movement by an adjusting screw 19 and a supporting rod 20. The bar 8 has a reduced pivotal bearing 21 in the upper end of the screw 19 and a similar bearing 22 at the upper end of the rod 20. The screw 19 is supported in the leg 5 of the base by means of an adjusting or tilting nut 23 threaded on the screw and supported in a supporting block 24 comprising a top trunnion plate 25 and a lower or bottom trunnion plate 26, the nut 23 being provided with an external flange 27 located between these two plates which are connected by screws 28. The trunnion plates 25 and 26 therefore provide bearings for the nut 23 and its flange 27, permitting rotation of the nut to adjust the screw 19 up or down. The lower or bottom trunnion plate 26 is mounted for pivotal movement with end bearings on two trunnions 29, secured in trunnion supports 30 mounted in openings in the opposite side walls of the supporting leg 5, and secured by welding them to these walls, the trunnions being removably mounted in their supports 30 by means of screws 31 passing through flanges 32 on the trunnions. It will be understood, that by operating the nut 23, the screw 19 will be raised or lowered to tilt the bed or frame 1 between the horizontal and vertical positions, or any intermediate inclined position between these two positions. The nut 23 may be operated by any suitable means, such, for example, as any suitable type of wrench 33, operating on an hexagonal head 34 of the nut, or it could be a ratchet type of wrench.

The opposite end of the bar 8 is supported by reduced pivotal bearing 22 on the upper end of the supporting rod 20. This rod passes through a pinchbind block 35 having an upward extension 36 which is split as shown at 37, the sides of which are connected by a binding screw 38. The lower end of the block 35 is pivotally mounted on the free inner ends of trunnions 39 supported in trunnion supports 40 mounted in openings in the side walls 6 of the leg 4 by which they are removably secured to the supports 40 by screws 42. In adjusting the angular position of the bed or frame 1, the pinch or binding section 36 is released or loosened by loosening the screw 38, then the bed is adjusted to the desired position by operating the nut 23 to adjust the screw 19. Then the screw 38 is tightened, clamping the split portion 36 about the rod 20 to provide additional support for the opposite end of the bed or frame 1.

It has been found that strictly horizontal or strictly vertical machines are limited to a smaller range of jobs or operations, as compared to a machine such as this one which can operate in both planes. The forming area of most of the prior machines is somewhat limited and congested for certain types of work. This machine has the advantages of a machine which can operate in both horizontal and vertical positions as well as any inclined position between the horizontal and vertical positions, as may best suit the forming of the particular article to be produced. This also permits tooling up in the horizontal position and then tipping the machine to the vertical position for running.

Slides at the Work Station

Mounted on or in the bed or frame 1 are the various tools and means for operating them for performing the desired operations on the work, such as a wire of any suitable cross section, such as round or flat wire in the form of ribbon metal or other forms. These operations

are performed at a forming area, which may also be termed a work station, at which are tools or means for supporting the work, and tools or means for performing the various operations on the work, with means for feeding the wire or stock to this area or station for the forming operations. In the present construction, at this area or station the bed or frame 1 is provided with an opening 43 around which are mounted tool slides 44, 45, 46 and 47. The opening 43 is of substantially rectangular form and the slides 44 to 47 are arranged to move toward and from this opening, one on each of the opposite sides thereof, and for purposes of identification slide 44 will be called the front slide, 45 the rear or back slide, 46 the right hand slide and 47 the left hand slide. Each slide is provided with means for mounting a tool for performing a forming or other operation on a work piece at the work station, these elements being omitted from the drawing as they would be different for different operations, but each slide is shown as provided with a surface 48 on which the means for mounting the tools may be secured. The surface 48 on the left hand slide 47 is on a removable support 48' secured to the slide by screws 48". This permits removal of this member to provide room for mounting a press unit when moved up to the forming area. Each slide is mounted in a suitable guide for sliding movement toward and from any support or other means for cooperation with the tools thereon in holding the work for these operations at the work station.

As shown in the drawings, each slide has tapered or inclined sides 49 operating in similarly tapered or dovetail type guideways 50 mounted on the bed or frame 1. Suitable means is provided for reciprocating these slides, such as the grooved cams 51, 52, 53 and 54 connected respectively with these slides, these cams being each mounted on one of the four operating shafts 55, 56, 57 and 58 mounted in suitable bearings on the frame or bed 1. In the arrangement shown each slide is operated by means of a roller 59 (FIGS. 13 and 14) operating in a suitably shaped groove 60 in their respective cams, the shapes of the cams, of course, being such as to impart the desired motions of each slide and the timing of these motions, required for the operation to be performed by the tool carried by each slide on the work at the work area or station. For purposes of identification, shaft 55 will be termed the front shaft when the machine is in the horizontal position and the top shaft when the machine is in the vertical position. Shaft 56 will be called the back shaft when the machine is in the horizontal position, and the lower shaft when the machine is in the vertical position, while shaft 57 will be called the right hand side shaft, and shaft 58 will be called the left hand side shaft.

Drive for the Shafts

These shafts are connected so that they are driven in unison and from a single driving unit, that is, shaft 57 is indicated as driven from the shaft 56 by bevel gears 61, shaft 55 is driven from shaft 57 by bevel gears 62, and shaft 58 is driven from shaft 56 by bevel gears 63. Shaft 55 is mounted in suitable bearings 64 in the frame or bed, shaft 56 is mounted in suitable bearings 65, shaft 57 is mounted in bearings 66, and shaft 58 is mounted in bearings 67, one of which is not shown as it is under the feed mechanism. One shaft, in this case the shaft 56, is driven from a suitable electric motor 68 through a suitable reducing drive 69 and a belt drive 70 to a pulley 71 connected with the shaft 56 through a suitable clutch 72, which may be controlled by any suitable means, such as a hand lever 73, for either connecting the drive to or disconnecting it from the shaft 56.

The motor 68 and the drive 69 are mounted on a motor plate 74 pivotally mounted on a pivot bar 75 supported at its opposite ends in supports 76 and 77 welded to the base 2. The free end of this plate is connected at 78 to a slideable bar 79 at one side of the plate 5 and connected at its lower end to a spring 80 connected at its lower end

to the leg 5. This provides a steady means for the end of the plate and the spring tends to hold the plate in its lower position. This mounting for the motor and the drive permits them to move with the bed or frame 1 as it is shifted between its various positions to maintain the proper driving connection to the shaft 56.

Mounted on one of the shafts, preferably on the right hand end of the front or top shaft 55, is a hand wheel 81 by which the various shafts, and the operative elements connected thereto, may be operated in tooling up and adjusting the machine.

Form Bracket

An important improvement in this machine is the provision of a new and improved form of form bracket 82 employed at the work area or station for mounting certain tool elements, particularly vertically movable elements, such, for example, as form slides, strippers or any tool element which is to be supported in an upright position, or any position over or above the bed or the slides mounted thereon at the working area or station, as well as supporting the means for operating any of these tool elements, such, for example, as levers for operating or shifting them in performing their functions in the forming operation. This improved form bracket is shown in detail in FIGS. 23 to 25, and the advantages of this bracket and the different ways in which it may be mounted and used are shown in FIGS. 10 to 14 and 17 to 22. It comprises a pair of upright laterally spaced legs 83 each provided with a foot 84 by which the bracket may be mounted on and secured to the bed or frame 1. For this purpose each foot is provided with a tongue 85 on its under side adapted to seat in channels or grooves 86 (FIGS. 10 and 18) in the surface of the bed, and by means of bolts 87 in elongated openings 88 in these feet, whereby the bracket may have limited forward and backward adjustment on the bed by means of adjusting screws 87.

The legs 83 are connected by an upright longitudinally extending supporting bar 90, located at the front of these legs and provided on its front side with an upright longitudinally extending flat mounting surface 91, extending the full width of the bracket, and this bar and surface are located a material distance above the lower ends of the legs and the feet 84 to provide a material clearance space, indicated at 92 (FIG. 23) between the legs and below the bar 90 for operation of tool elements, or the slides supporting elements at the work station. This upright mounting surface 91 and the bar 90 provide means for mounting a tool or tool support both at different heights with respect to the bed 1, and different longitudinal positions on this bar 90, and therefore on the form bracket 82. It provides means by which a great variety of form holder blocks may be mounted to best suit the particular type of tooling situation.

To facilitate properly mounting and supporting various elements on the surface 91 it may be provided with a longitudinal channel or groove 93 to receive the cooperating tongues of the same width on a bearing or other support mounted on the bracket, or a key in an aligned channel in the mounted member, an example of which is shown in FIGS. 19 and 20, in which one bearing block 94 is shown mounted on this surface, using a key 95 seated in the groove 93 and a center groove on the block 94, instead of a tongue on this block. The block 94 is secured to the form bracket by screws 96 passing through properly located holes 97 in the bar 90, and there may be any desired number of these holes, so located as to be capable of supporting the bearing block 94 at different longitudinal positions on the surface 91 of the bar 90. By locating the grooves for the key 95, and the tapped openings for the screws 96, above or below the center line of the block 94, it may be supported on the surface 91 at different vertical elevations or different vertical positions by inverting it, as indicated by the full lines 98 and broken lines 99 (FIG. 20) at the upper and lower ends of the

block 94. These bearing blocks are shown in FIGS. 19 and 22 as forming bearing supports and guideways for vertically movable forming slides 100 and 101. Slide 100 is mounted in a guide channel in the front of the bearing block 94, and retained therein by a front or cap plate 102 secured on the front of the block by suitable screws 103, and the slide 101 is mounted in a similar channel in the rear side of the block and held therein by the surface 91.

The upright legs 83 of the form bracket are provided with upright extensions 104 provided with means for operating suitable operating levers for operating the slides 100 and 101. The bracket is also strengthened by means of a longitudinal web 105 extending between, connecting and integral with the upright extensions 104. The means for mounting the levers comprises a pair of bearing openings 106 and 107 in the extensions 104, and with the opening 106 spaced forwardly of the opening 107. These openings are adapted for mounting transverse pivot pins, one of which is shown at 108, in the openings 107 and forming a pivot bearing for the levers 109 and 110 connected to the respective slides 100 and 101. The levers are mounted on this pin by bearings 111 and 112, and each lever is provided with an additional bearing 113 and 114 spaced forwardly of the bearings 111 and 112. The bearings 113 and 114 may be mounted on a pin similar to the pivot pin 108 in the forward openings of the bracket, thus providing different leverages for the levers 109 and 110, and different lengths of movement for the elements operated by these levers. In the arrangement shown, each lever is operated by a roller 115 running in a cam groove 116 in a cam 117 or 118 mounted on the back shaft 56.

The lever 109 is shown connected by a bolt 119 at its forward end directly to a block 120 mounted for vertical adjustment on the slide 100 by means of screws 121 in elongated slots 122, but there is shown in connection with the lever 110, an end member 123 detachably mounted on the forward end of the lever 110, and connected to the block 124 mounted for vertical adjustment on the slide 101. The same end member may be used on the lever 109 if desired. It will be seen this lever end 123 is offset at 125, so that the portion 126 secured to the lever and the free end portion 127 secured to the block are not in alignment, but are laterally offset with respect to each other. The end member is secured to the lever 110 by the bolts 128, and may be mounted on either side of this lever. Thus if it is mounted on the opposite side from the position of FIG. 21, as shown in FIG. 22, it may be connected to a form slide 101 located at a different longitudinal position on the bar 90 or surface 91 of the form bracket, or if the end member 123 is reversed, still a different position may be secured for connection of the offset 127 to a form element mounted on the bracket.

An important and distinct advantage of the novel and improved form bracket 82 is that it may be mounted in different positions on the bed or frame 1, and in different positions with relation to the forming area or work station. For this purpose the bed or frame is provided with two pairs of lands, or supporting surfaces, for the feet of the bracket. One pair is shown at the rear of the work station, of which the opening 43 is a part, this pair being indicated at 129 and 130, and the other pair arranged at right angles thereto comprising the surfaces 130 and 131. Therefore, the surface 130 is common to both pairs. For mounting the form bracket 82 to the rear of the opening 43, the feet 84 are mounted on the two lands 129 and 130, as shown in FIG. 10, and as indicated in dotted lines in FIG. 13, and secured by the bolts 87 to the bed 1. As previously indicated, the bolts 87 pass through elongated openings 88 in the feet, and the bracket is capable of limited adjustment forwardly and backwardly by means of the adjusting screws 89, and then is clamped in the adjusted position by tightening up the bolts 87. When so mounted the bracket is considered as back mounted, as it is to the rear of the opening 43, and the levers 109

and 110 mounted thereon are operated from cams 117 and 118 on the back shaft 56. The form bracket 82 can be mounted in a position at right angles to this position by locating the feet on the two lands 130 and 131, as indicated by the full lines in FIG. 13 and as shown in FIG. 11. The bracket in this position is termed as being side mounted, and is secured to the bed or frame 1 by the same bolts 87 with adjusting screws 89. In this position the levers 109 and 110 are operated by the cams 117 and 118 on the right hand side shaft 57.

By being able to mount this form bracket in either one of these two positions, the versatility of the machine is greatly increased, as it permits a large number of variations in the mounting and arrangement of the forming tools and associated elements at the work station. Thus, for example, with the back mounting for this bracket the tools, such as the form slides 100 and 101, mounted on the front of the bracket, may be adjusted to different longitudinal positions relative to the frame 1, or parallel to the front and back shaft 55 and 56, while in the side mounting position these elements could be adjusted and located in different positions transversely of the bed or frame 1, and parallel to the side shafts 57 and 58, and tools mounted on this bracket may be operated either from the rear shaft 56 or the side shaft 57.

When this form bracket 82 is mounted on the right side position it provides a very open area for the front, rear and left hand forming slides 44, 45 and 47. This form bracket is also so arranged that at least two vertical motions can be provided when the bracket is mounted at either of the two positions. Also more than one form holder can be mounted on the face 91 of this new type of bracket, when such would prove to advantage for certain types of formations, particularly in the case of formations where a relatively wide width of formation may be produced. In such cases two form holders, each one to support a form for use in a forming of work at either extremity of the wire or work piece might be desired, or in other instances possibly as many as three form holders or more might prove to advantage. By such arrangement the simplest type of forms required for the particular formation can be supplied, rather than requiring complicated types of forms as might be necessary if the old fixed type of form bracket was being used to support the form.

Auxiliary Form Bracket

This construction of form bracket 82, with the transverse bar 90 and the vertical transverse mounting surface 91 at the front of the bracket, also permits the use of an auxiliary form bracket 132, shown in detail in FIGS. 26 to 28. This comprises a base 133 which may be mounted on the surface 91, as indicated in FIG. 29, and secured in any desired longitudinal position thereon by securing bolts or screws 134 through any of the openings 97 in the form bracket 82 and a key 135 seating in the groove 93 and a similar groove 136 in the base 133. Extending upwardly and laterally from the base 133, and connected by an intermediate web 137, are two legs 138 laterally spaced and provided with bosses 139 on their inner surfaces between which may be mounted an operating lever, as indicated at 140 in FIGS. 11, 17 and 18, mounted on a pivot pin 141. The legs 138 and bosses 139 are provided with two laterally spaced openings 142 and 143, so that the lever may be mounted in different locations with different fulcrums or leverages, and also imparting different strokes or lengths of movement to an element operated by the lever. This lever, as shown in FIGS. 17 and 18, is provided with a detachable end member 144 secured in adjustable positions by the bolts or screws 145, and connected to a vertically movable slide 146 by a projecting end portion 147 located in a notch 148. The member 146 may be a vertical form slide mounted in bearing

blocks 149 (FIG. 17), similar to the bearing block 94 (FIG. 20).

As shown in FIG. 17, the combination of the main form bracket 82 and the auxiliary form bracket 132 permits the use, as shown by way of example, of one form slide 146 operated by lever 140 on the auxiliary bracket from a cam 150 on the back shaft 56, while another form slide 151, similar to the slides 100 or 101 (FIG. 20), may be operated by a lever 110 on the main form bracket 82 and a cam 118 on the right hand side shaft 57, the lever 110 of FIG. 17 being shown as the same lever 100 of FIGS. 20 and 21, and having the same detachable lever end member 123.

It will thus be seen, that the possibility of mounting the main form bracket 82 in either of two positions with respect to the forming area or work station and at right angles to each other, together with the improved and novel form of this form bracket, permits the use of an increased number of different forming tools or elements, and in a large number of different positions, and this versatility is still further increased by the use of the novel auxiliary form bracket 132, and the fact it may be mounted on the main form bracket 82.

It will be noted, for example, that when the form bracket 82 is located in the back mounted position, the two side slides 46 and 47 operate in a plane parallel to the mounting surface 91 at the front of this form bracket, while when the form bracket is in the side mounted position the front slide 44 and rear slide 45 operate in a plane parallel to the mounting surface 91, which, it will be evident, permits the use of a number of different forming tools or elements, and a number of different relations with respect to each other, for different forming operations on work pieces at the work station, giving a versatility which is impossible with the old type of fixed form bracket which has been commonly employed in this type of machine, in which a single fixed bearing for a vertical slide only was provided, due to the limited space which was available with this old type of fixed bracket.

Press Unit

Another advantage of this improved form bracket 82, and the possibility of its being mounted at different positions on the bed or frame 1, is that it permits different mountings and locations of other units for performing operations on work pieces in the forming area. Thus, for example, these improved features permit mounting of such units, as press units, nearer to the form bracket and other forming elements in the forming area, and also permit the use of one or more of these press units in conjunction with the other forming tools in the forming area, as well as the use of an improved form of press unit.

This improved form of press unit is shown in detail in FIGS. 30 to 33, and is indicated as a whole by the numeral 152 in FIG. 10, with the form bracket 82 in the back mounted position. A single one of these press units 152 is shown between the feed mechanism 153 for the wire stock and the work station, including the opening 43 and the tools carried by the slides 44 to 47, and slides or other tool elements mounted on the form bracket 82. It will be seen this press unit 152 is arranged so that it is operated from the front or top shaft 55. As shown in FIG. 11, with the form bracket 52 in the side mounted position, greater space is provided, so that two of these press units 152 may be mounted side by side between the feed mechanism 153 and the work station and slides carried by the form bracket 82. In this arrangement both press units are operated from the front or top shaft 55. Still another possible arrangement of press units is shown in FIG. 12, where when the main form bracket 82 is in the side mounted position, two of the press units may be used, one operated from the front or top shaft 55 and the other operated from the back shaft 56. In this figure the right hand unit 152 is operated from the shaft 55, and the left hand unit from the shaft

56. The ability to operate these two presses from these positions permits operations from front or back on a work piece. For example, one may punch or pierce from the front and one from the back. The ability to operate these presses from either of these two positions offers further advantage when the machine is tilted to the vertical position, in that the press can be so located that the scrap will fall by gravity and present less problems in ejecting. Also when the bracket 82 is mounted in the right side position it would prove to advantage in certain types of formations. A particular one, for example, is that a press unit 152 in either the rear or front position may be mounted up close to the forming area.

This improved press unit is so constructed as to be assembled complete as a unit, and mountable as such in any of the locations indicated on the bed or frame 1. It comprises a base plate 154 on which the elements of the press are mounted and which, in turn with the elements mounted thereon, may be mounted on the bed 1, as shown in FIG. 33, it being secured by bolts 155 with T heads or nuts 156 in T slots 157 in the bed 1, and it is further secured against longitudinal movement by suitable keys 158 in aligned channels in the bed 1 and the bottom of the plate 154. The press unit comprises in addition to the plate 154 a back block 159 mounted thereon by means of the screws 155 and 159a, together with a suitable locking key 159b, and a frame 160 located forwardly of the back block. This frame includes laterally spaced upright side members 161, and a connecting lower member 162 by which it is mounted on the base plate 154 by means of the screws 163 and the key 164. Also mounted on this connecting member 162, and secured by the screws, are right and left hand tapered gibs 165 forming a guideway for the dovetailed lower portion 166 of a slidable ram 167. This ram is operated by a lever 168 pivotally mounted on a fulcrum shaft 169 mounted at its opposite ends in the side members 161 of the frame, and connected by the link 170 to the ram. This link is pivoted to the lever at 170a and to the ram at 170b. 20 This lever is operated from either the shaft 56 or 57 by an eccentric 171 embraced in a bearing in a link 172, the link shown comprising a body member 173 and a cap 174, each providing half of a bearing for the eccentric 171 and connected by the screws 175, the link being connected to the lever 168 by the eccentric pin 176. To back up the shaft 56 and the eccentric under the longitudinal pressures incident to operation of the ram in the press operations, a bearing block 177 is secured to the frame 160 on each side of the eccentric 171 by the screws 178, and each providing a bearing 179 for the shaft. 25

The back block 159 and the ram provide supports for the die set for the press operations on the work pieces. These are indicated diagrammatically by bolster plate 180 mounted on the front of the back block 159, and a supporting block 181 at the front of the bolster plate, these elements being secured to the back block by screws 182. A similar supporting block 183 is secured on the front end of the ram 167 by the screws 184, and these blocks provide means for mounting tools (not shown) for the press operations, such, for example, as piercing, punching, drawing, forming, and coining operations, before cutting the work piece from the strip stock. The tool blocks 181 and 183 of the die set may be kept in alignment by guide pins 185 carried by the block 183, and guided for sliding movement in openings 186 in the block 181. The back block 159 and the frame 160 are connected by the tie rods 187, which take the stresses between these two members incident to the press operations. It will thus be seen the press unit may be assembled as such on the bed or frame 1, it being merely necessary to make the proper connection to the eccentric on the operating shaft. Also that the stresses due to 30 the press operations are absorbed in the press unit itself, 35 40 45 50 55 60 65 70 75

rather than being transmitted to the bed and the means of securing the unit to the bed.

This new bed or frame construction, including the opening 43 therein, provides facilities for supporting a form from the under side of the bed, and also operating it from the underside. Such an arrangement is shown in FIGS. 15 and 16, in which a bracket 183 is mounted in the opening 43 from the under side of the bed 1, by means of the screws 189 passing through flanges 190 at opposite ends of the bracket, and overlapping the under surface of the bed at opposite sides of the opening. In the arrangement illustrated by way of example, it includes a form 191 mounted in the bracket, and also a stripper 192 associated with this form, mounted on a reciprocable rod 193 connected by a split adjustable block 194 clamped on the rod and pivotally connected at 195 to a lever 196, this particular lever being formed in two sections 197 and 198, mounted of a pivot pin 199 mounted in and extending between two bearing lugs 200 on the under side of the bed 1, and connected by the screws 201. This lever, and therefore the stripper, is shown as operated by a roller 202 running in a groove 203 of the cam 204 mounted on the back shaft 56. The front, rear and end side slides 44 to 48 may operate in conjunction with these elements 191 and 192, two of the slides only, 44 and 45, being shown in FIG. 15. This arrangement proves particularly beneficial when the machine is being operated in the vertical position, in that it provides means for an orderly ejection of certain types of formations, on a horizontal rail, for example, extending from the form which often facilitates later operations, such as assembling, packaging, and so forth. It also provides increased visibility in the forming area and greater accessibility to the tools.

The slides and other tool elements at the forming area or work station, are operated in conjunction with feeding means 205 for the raw stock, means 206 for gripping it after the feeding operation to prevent its being shifted backward on backward movement of the feed slide, and the cut-off 207 for the work after feeding to the working area of work station, where certain operations are performed thereon. The feed mechanism is shown more in detail in FIGS. 34 to 36, and comprises a feed head 208 mounted to slide toward and from the forming area on a slide-way 209. This carries a gripping jaw 210, operated by a lever 211 pivotally mounted at 212 in the head, and operated by a link 213 from a lever 214 pivoted on a supporting bracket 215 mounted on the bed 1. The lever 211 may slide on the link 213 to permit longitudinal movement of the head or block 208, the lever 214 being operated in certain timed relation with the longitudinal movement of this block from a suitable cam 216 on the front shaft 55, to grip the work for the feeding operation and to release it for the backward movement of the feeding head. These forward and backward movements of the feeding head are imparted from a crank 217 mounted on the side shaft 58, through a link connection 218 pivotally connected at one end at 219 to the crank 217 by a block adjustable in a slot 220 to vary the stroke of the feeding means, and pivotally connected at its opposite end 221 to a lever 222 pivotally mounted by a bearing pin 223 in a forked bracket 224 mounted at the end of the bed 1 by suitable screws 225, and the upper end of this lever 222 is connected by a link 226 to the slidable head 208 of the feed mechanism.

The gripping means to prevent reverse movement of the wire on backward movement of the feed mechanism is shown in FIGS. 37 and 38, as comprising a die 227 through which the wire is fed, and which is carried on a block or bracket 228 secured in position on the top of the bed or frame 1 between the feed mechanism and the forming area, as shown in FIG. 10, by a screw 229 having a T head 230 in a T slot 231 in the bed. A pin or slide 232 is mounted to slide in the block in certain timed relation with the feeding operation, to grip the wire

indicated at W by the free end shown in dotted lines at 233, and operated by a lever 234 pivoted to the bracket at 235, in turn operated by a roller 236 from a cam 237 on the shaft 55. The gripping rod is retracted by means of a spring 238. The cut-off means is shown in FIGS. 39 and 40, comprising a block 239 secured on the bed 1 by a bolt 240 and a T nut 241 in the T slot 231 in the bed. Means may be provided for adjustment of this cut-off, comprising a rack 242 mounted on the bed and meshing with a pinion 243 operated by a bolt 244 with a non-circular, such as a hex, nut 245. Mounted on the block 239 in a dove tail guideway is a slide 246 on which a cut-off blade 247 is adjustably mounted having a cutting edge 248 movable across the end of a guide quill 249, adjustably mounted in a block 250 mounted on the end of the block 239. The slide 246 is operated by a roller 251 operating in a cam groove 252 in a suitable cam 253 mounted on a shaft 55.

If instead of a round wire, a flat wire or ribbon is to be used as the work material, then the quill 249a of the cut-off would have a correspondingly wide guide opening 256, as shown in FIG. 41, with a correspondingly wide blade 257.

In the various figures of the drawing the center line of the wire is indicated by the letter W, while the center line of the side slides 46 and 47 is indicated by the line S. Another advantage of the novel construction of form bracket 82 is that the cut-off 207 may be located much nearer to the tool elements at the forming station, which is desirable for certain operations. This form bracket design, including the wide flat mounting surface 91, provides means to which a great variety of form holder blocks may be mounted to best suit the particular type of tooling situation. This type of construction, wherein the form is held in a separate block, rather than being supported in an opening integral with the basic form bracket, permits the positioning of the cut-off unit as close to the forming position as required by some critical formations, particularly those requiring short feed lengths. This has always been a problem and limitation of machines with the old fixed type of form bracket previously used.

The wire on its passage to the feed mechanism may pass through the usual one or more straighteners, indicated in full lines at 254 in FIG. 10 and in dotted lines in FIG. 11, mounted on a suitable supporting arm 255 secured to the bed or frame 1.

It will be seen from the above, that this machine has a number of important improvements over the old type of machine with the fixed bed or frame and the fixed construction of form bracket, providing more clearance and free space in the forming area for the tool elements and operating slides therefor, and providing means for mounting and using a greater number of variations of positions for the tool elements, and the operations that may be performed thereby.

Having thus set forth the nature of my invention, I claim:

1. A multiple slide metal wire or ribbon forming machine comprising: a supporting base; a substantially rectangular frame; means pivotally securing said frame to said base for movement of said frame on an axis passing near one side edge thereof between horizontal and vertical positions; said frame when in the horizontal position having a top side and an underside; means providing a forming station on said frame having an opening extending through said frame and accessible from both the top side and underside thereof; a plurality of tool slides adapted to carry forming tools; means mounting said slides on the top side of said frame for movement toward and from said station for operation on a work piece at said station; a plurality of shafts rotatably mounted on said frame at the side edges thereof and operatively connected to jointly rotate, none of said shafts being coaxial with said axis; drive means from said shafts to said tool slides for moving said slides in a controlled manner;

means for selectively tilting said frame in stepless fashion about said axis between the horizontal and vertical positions and retaining it in either position or in any intermediate angular position; and means for driving said shafts comprising a driving motor supported on said base, a driven member supported on said frame and arranged to drive one of said shafts, a driving connection between said motor and driven member, and means mounting said motor on said base so as to automatically maintain the proper driving relationship of said motor, said driven member and said driving connection regardless of the angular position of said frame relative to said base.

2. A multiple slide metal wire or ribbon forming machine comprising: a supporting base; a substantially rectangular frame; means pivotally securing said frame on said base for movement of said frame on an axis passing near one side edge thereof between horizontal and vertical positions; said frame when in the horizontal position having a top side and an underside; means providing a forming station on said frame having an opening extending through said frame and accessible from both the top side and underside; a plurality of tool slides adapted to carry forming tools; means mounting said slides on the top side of said frame for movement toward and from said station for operation on a work piece at said station; a plurality of shafts rotatably mounted on said frame at the side edges thereof and operatively connected to jointly rotate, none of said shafts being coaxial with said axis; drive means from said shafts to said tool slides for moving said slides in a controlled manner; means for selectively tilting said frame in stepless fashion about said axis between the horizontal and vertical positions and retaining it in either position or in any intermediate angular position; means for driving said shafts comprising a driving motor supported on said base, a driven member supported on said frame and arranged to drive one of said shafts, a driving connection between said motor and driven member, and means mounting said motor on said base so as to automatically maintain the proper driving relationship of said motor, said driven member and said driving connection regardless of the angular position of said frame relative to said base; a form holder detachably secured to the underside of said frame in alignment with said opening; tool means mounted on said holder; and an operative driving means extending on the underside of said frame and connecting said tool means and one of said shafts.

3. A metal forming machine comprising a frame, means providing a work station on said frame including a form bracket comprising laterally spaced upright legs having mounting feet at the lower ends thereof, said frame provided with three footing surfaces arranged in two pairs at right angles to each other with one pair located to the rear of the work station and the other pair at another side thereof, said feet of the form bracket adapted to seat on either pair of footing surfaces to mount the bracket at the rear of the work station and at one side thereof, means for detachably securing the feet to the frame, said bracket including a transverse bar connecting said legs and spaced above the lower ends thereof, said bar provided with an upright longitudinal mounting surface extending the length thereof providing means for supporting tool elements at different longitudinal positions on the bracket, tool slides adapted to carry forming tools, means mounting the slides on the frame for movement toward and from the work station for operation of the tools on a work piece at said station, and means for operating said slides.

4. A metal forming machine comprising a frame, means providing a work station on said frame including a form bracket comprising laterally spaced upright legs having mounting feet at the lower ends thereof, said frame provided with three footing surfaces arranged in two pairs at right angles to each other with one pair located to the rear of the work station and the other pair at another side thereof, said feet of the form bracket adapted to seat on either pair of footing surfaces to mount the

bracket at the rear of the work station and at one side thereof, means for detachably securing the feet to the frame, said bracket including a transverse bar connecting said legs and spaced above the lower ends thereof, said bar provided with an upright longitudinal mounting surface extending the length thereof providing means for supporting a tool element at different longitudinal positions on the bracket, an operating lever for said tool element mounted on the bracket, shafts mounted on said frame one to the rear of said work station and one at right angles thereto at one side of said station, means on the shafts for operating said lever when the bracket is in the rear and side mounting positions, and means for driving the shafts.

5. A metal forming machine comprising a base, a frame mounted on the base, means providing a work station on said frame including a form bracket comprising laterally spaced upright legs having feet secured to the top of the frame, said bracket also including a transverse bar connecting said legs and spaced above the lower ends thereof, said bar provided with an upright longitudinal mounting surface providing means for supporting tool elements at different longitudinal positions on the bracket, a lever mounted on the bracket for operating one of said tool elements, an auxiliary form bracket mounted on said first bracket, a lever mounted on the auxiliary bracket for operating another of said tool elements and positioned to operate in a plane at right angles to that of the first lever, shafts mounted on the frame at right angles to each other, operative connections from the shafts to the respective levers on the brackets, and means for driving the shafts.

6. A metal forming machine comprising a base, a frame mounted on the base, means providing a work station on said frame including a form bracket comprising laterally spaced upright legs having feet secured to the top of the frame, said bracket also including a transverse bar connecting said legs and spaced above the lower ends thereof, said bar provided with an upright longitudinal mounting surface at the front of the bracket providing means for supporting a tool element at different longitudinal positions on the bracket, a lever mounted on the bracket for operating said tool element, a shaft mounted on the frame to the rear of the bracket, an operative connection from the shaft to the lever, and means for driving the shaft.

45 7. A metal forming machine comprising a base, a frame mounted on the base, means providing a work station on said frame including a form bracket comprising laterally spaced upright legs having feet secured to the top of the frame, said bracket also including a transverse bar connecting said legs and spaced above the lower ends thereof, said bar provided with an upright longitudinal mounting surface at the front of the bracket providing means for supporting tool elements at different longitudinal positions on the bracket, each leg including an upright extension providing means for mounting an operative lever for a tool element mounted on the bracket, an operative lever mounted on each leg and connected with a tool element mounted on the bracket, a shaft mounted on the frame to the rear of the bracket, operative driving connections from the shaft to the levers, and means for driving the shaft.

8. A metal forming machine comprising a frame, means providing a work station on the frame including a form bracket comprising laterally spaced upright legs having feet at their lower ends secured to the top of the frame, said bracket also including an upright transverse bar connecting said legs at the front of the bracket and spaced above said feet, said bar provided with a longitudinal mounting surface providing means for supporting tool elements at different longitudinal positions on said bar, at least one of said legs including an upright extension extending above the bar providing means for mounting an operative lever for a tool element mounted on the bracket, an operative lever mounted on said extension, a shaft mounted on the frame to the rear of the bracket,

an operative driving connection from the shaft to the lever, and means for driving the shaft.

9. A metal forming machine comprising a frame, means providing a work station on the frame including a form bracket comprising laterally spaced upright legs having feet at their lower ends secured to the top of the frame, said bracket also including an upright transverse bar connecting said legs at the front of the bracket and spaced above said feet, said bar provided with a longitudinal mounting surface providing means for supporting tool elements at different longitudinal positions on said bar, at least one of said legs including an upright extension providing means for mounting an operative lever for a tool element mounted on the bracket, an operative lever mounted on said extension, an auxiliary form bracket mounted on the first bracket, a lever mounted on the auxiliary bracket for operating another of said tool elements and positioned to operate in an upright plane at right angles to that of the first lever, a shaft mounted on the frame to the rear of each bracket, operative connections from the shafts to the respective levers on the brackets, and means for driving the shafts.

10. A metal forming machine comprising a frame, means providing a work station on the frame including a form bracket provided on the front thereof with an upright longitudinal mounting surface providing means for supporting tool elements at different longitudinal positions, an operative lever pivotally mounted on the bracket to operate in a vertical plane, an end member for the lever comprising a main portion and a laterally offset portion provided with means for connecting it to a tool element on the bracket, securing means detachably mounting the main portion of the end member on a side of the lever and adapted to secure said end member to either side of the lever and with the offset extending in either lateral direction therefrom, a shaft located to the rear of the form bracket, an operative connection from the shaft to the lever, and means for driving the shaft.

11. A metal forming machine comprising a frame, means providing a work station on the frame including a form bracket provided on the front thereof with an upright longitudinal mounting surface providing means for supporting tool elements at different longitudinal positions on the bracket, an operative lever, means pivotally mounting the lever on the bracket to operate in an upright plane, an end member for the lever provided with means for connecting it to a tool element mounted on said upright surface of the bracket, cooperating means on the lever and the end member adapted to secure the end member to either lateral side of the lever for connection to tool elements in different longitudinal positions on said mounting surface, a shaft located to the rear of the form bracket, an operative connection from the shaft to the lever, and means for driving the shaft.

12. A metal forming machine comprising: a frame; means providing a work station on said frame with tool means for performing operations on a work piece at said station; means for feeding wire or ribbon stock to said station; a self-contained fully assembled press unit detachably mounted as a unit on said frame between said feeding means and said station; said press unit including a base plate adapted to be detachably secured to said frame, a movable ram mounted on said base plate and adapted to carry a tool, means mounted on said base plate and arranged to support a die, and means for operating said ram including a lever pivotally supported by said base plate and operatively connected to said ram; a rotatable shaft mounted on said frame; and an operative connection from said shaft to said lever; said base plate supporting all of the other parts of said press unit whereby said press may be attached to or detached from said frame by attaching or detaching said base plate,

5 13. A metal forming machine comprising a frame, means providing a work station on the frame including a form bracket comprising laterally spaced upright legs having feet at their lower ends secured to the top of the frame, said bracket also including an upright transverse bar connecting said legs at the front of the bracket and spaced above said feet, said bar provided with a longitudinal mounting surface providing means for supporting tool elements at different positions on said bar, said legs 10 each including an upright extension, said extensions provided with a plurality of means for supporting a pivot pin for an operating lever for a tool element mounted on the bracket, said means for supporting the pivot pin being located to support this pin at different distances from 15 said mounting surface for supporting levers with different fulcrum lengths with respect to a tool element mounted on said surface, an operative lever mounted on a pivot pin so mounted, a shaft mounted on the frame to the rear of the bracket, and an operative driving connection 20 from the shaft to the lever.

14. A multiple-slide metal forming machine comprising: a supporting base; a substantially rectangular frame; pivot means mounting the frame on said base for movement of the frame on an axis passing near one side edge thereof between horizontal and upright positions; means providing a forming station having an opening on said frame; tool slides adapted to carry forming tools; means mounting said slides on the frame for movement toward and from said station for operations of the tools on a work piece at said station; a form bracket comprising 25 laterally spaced upright legs having mounting feet at the lower ends thereof; said frame provided with three footing surfaces arranged in two pairs at right angles to each other with one pair located to the rear of the work station and the other pair at another side thereof; said feet 30 of the form bracket adapted to seat on either pair of footing surfaces to mount the bracket at the rear of the work station or at one side thereof; means for detachably securing the feet to the frame; said form bracket including a 35 transverse bar connecting said legs and spaced above the lower ends thereof; said bar provided with an upright longitudinal mounting surface extending the length thereof of providing means for supporting tool elements at different longitudinal positions on the form bracket; means 40 for operating said slides including shafts mounted on said frame and operatively connected to each other, none of said shafts being coaxial with said axis; means for tilting the frame from the horizontal to the vertical and to different intermediate angular positions about said pivot 45 means and retaining it in different positions; and means 50 on the under side of said frame for mounting a form holder in alignment with the opening in said forming station whereby said frame may be positioned and retained in any position between the horizontal and vertical with the form bracket mounted at either the rear or side of the forming station on the upper side thereof or with the form holder mounted on the under side of the frame.
